CLAIM

The ornamental design for a bottom electric heating element for a cooking oven, as shown and described.

DESCRIPTION

FIG. 1 is a top plan view of a bottom electric heating element for a cooking oven showing our new design and the bottom plan view is identical;

FIG. 2 is a front elevation view thereof taken on the line 2—2 of FIG. 1;

FIG. 3 is a rear elevation view thereof taken on the line 3—3 of FIG. 1;

FIG. 4 is a side elevation view thereof taken on the line 4—4 of FIG. 1 and the left side elevation view thereof is identical; and,

FIG. 5 is an enlarged top plan view of a second embodiment of a bottom electric heating element for a cooking oven, the sole difference being the shape of the front edge thereof, with the elevational views being substantially identical to FIGS. 2, 3 and 4.
